J. H. WISSMAN

HOT WATER BOILER

Filed Nov. 21, 1921

Inventor
Joseph H. Wissman
by *[Signature]* Attorney

UNITED STATES PATENT OFFICE.

JOSEPH H. WISSMAN, OF EAST CLEVELAND, OHIO.

HOT-WATER BOILER.

Application filed November 21, 1921. Serial No. 516,747.

To all whom it may concern:

Be it known that I, JOSEPH H. WISSMAN, a citizen of the United States, and resident of East Cleveland, in the county of Cuyahoga and State of Ohio, have invented certain new and useful Improvements in Hot-Water Boilers, of which I hereby declare the following to be a full, clear, and exact description, such as will enable others skilled in the art to which it appertains to make and use the same.

The objects of the invention are to provide a boiler for heating purposes, enclosing a central combustion chamber, to enable the water to be heated quickly.

The principle of operation includes a circulating system in which the water is caused to take a downward direction from the inlet at the top of the boiler, and then circulates around and about the combustion chamber and enlarged passages leading therefrom, and when it has absorbed heat from contact with the heated surfaces of the aforesaid passages, is then directed upwards, passing again over the aforesaid heated surfaces, and finally into the circulating system of the house.

The invention further includes the employment of vertical external passages in which the water flows downwardly, and horizontal passages communicating therewith, and a central combustion chamber and an outlet flue therefor, the aforesaid outlet flue being provided with vertically spaced and horizontally enlarged portions, connected by means of vertical flues that extend through the aforesaid horizontal water passages.

The invention also includes a boiler construction composed of a multiple number of superimposed horizontal sections, in which the water flows alternately in opposite directions.

The invention further includes the combination and arrangement of parts and construction of the various parts, hereinafter described, and specifically pointed out in the claims.

In the accompanying drawings, Fig. 1 is a vertical central section of the boiler on line 1—1, Fig. 2; Fig. 2 is a side elevation thereof; Fig. 3 is a plan of the bottom section thereof; Fig. 4 is a plan of the next adjoining section; Fig. 5 is a plan of the third section, and Fig. 6 is a plan of the top section.

As many sections may be employed as may be necessary to raise the boiler to any height desired.

In these views, A, B, C, D, represent the bottom, intermediate and top sections, respectively.

The bottom section comprises a combustion chamber, A', resting upon a hollow base, A'', which is used as an ash pit when coal is used as fuel.

A door, A³, is provided with a damper, A⁴, for admission of air.

This combustion chamber A' is enclosed on the sides and top by means of a water jacket, A⁵, and central and marginal outlet flues A⁶, A⁷, convey the products of combustion to the section above.

The section B rests upon the bottom section A, and is provided with the central horizontal shallow recesses, B⁸, B⁹, for the circulation of the products of combustion and which are formed in the top and bottom walls thereof respectively, and register with reversed recesses C' and A⁷ in the section C above and bottom section A respectively, the opposed recesses forming flue chambers or passages between them for products of combustion.

The flue chambers formed in this manner are then connected by means of spaced vertical flues, B⁴, B⁵.

The third section, C, is provided with similar horizontal recesses, C', C'', at bottom and top which register with the recesses, B⁸, and D', in the sections respectively below and above the section, C. Flues, C³, C⁴, connect the chambers formed in this manner.

The upper section, D, is provided with the recess, D' in its lower face, and also is provided with a central outlet flue, D², communicating between the sections, C and D.

The water enters the upper section at D³, and after passing over the central flue chamber beneath the upper section, travels downwardly through an external pipe, D⁴, which connects the upper section with the next one, C, below.

This pipe is cast integrally with the walls of the adjoining sections, and a sleeve, D⁵, connects the sections together.

The water, entering the chamber, C, traverses the same horizontally over the flue chamber between the sections, B and C, and thence travels downwardly through the external pipe, C⁴, cast integrally with the

walls of the sections, into the chamber, B, and the parts of the pipe are connected by means of the sleeve, C⁵.

The water passing through this chamber 5 is directed downwardly through the pipe, B⁵, which extends to and communicates with the section A, adjacent to its bottom.

Thence the water flows around the section A, and upwardly towards the outlet, A⁸, at 10 the top of the section.

In operation, the water, entering in the upper section, descends through the several sections to the lower section, and rises therein to the top of this section, and becomes 15 very hot before it reaches the lower section, after passing over the horizontally enlarged flue chambers between the sections.

It will be seen that the contacting surfaces of the sections are flat and make tight 20 joints with each other, which prevents the escape of the products of combustion.

Bolts, T, T, connect the sections together.

Having described the invention, what I 25 claim as new, and desire to secure by Letters Patent, is:

1. In a hot water boiler, superimposed sections, provided with circulating passages for the products of combustion and water, comprising a bottom section, a water chamber enclosing the sides and top wall thereof, and a multiple number of hollow sections superimposed thereon, the top section provided with a water inlet opening and with 30 a central horizontal recess in its lower wall, and the next adjoining section provided 35 with a complementary recess in its upper wall and with a corresponding recess in its lower wall, and the next adjoining section provided with similar recesses in its upper and

lower walls, said recesses in said adjoining sections registering with each other and forming horizontally extending flue chambers, said chambers connected by vertical pipes, and exterior vertical pipes connecting the upper parts of said superimposed hollow sections with the lower parts of the next adjoining sections below. 40

2. In a hot water boiler, superimposed sections, provided with circulating passages for the products of combustion and water, comprising a bottom section, a water chamber enclosing the sides and top wall thereof, and a multiple number of hollow sections superimposed thereon, the top section provided with a water inlet opening and with a central horizontal recess in its lower wall, and the next adjoining section provided 50 with a complementary recess in its upper wall and with a corresponding recess in its lower wall, and the next adjoining section provided with similar recesses in its upper and lower walls, said recesses in said adjoining sections registering with each other and forming horizontally extending flue chambers, said chambers connected by vertical 55 pipes, and exterior vertical pipes connecting the upper parts of said superimposed hollow sections with the lower parts of the next adjoining sections below, said vertical pipes being cast in two portions integral with said sections, and sleeves connecting said pipe 60 portions. 70

In testimony whereof, I hereunto set my hand this 14th day of Sept. 1921.

JOSEPH H. WISSMAN.

In presence of—

Wm. M. MONROE,
Sol W. WYMAN.
